UNITED STATES PATENT OFFICE.

PIERRE BOISSET, OF PARIS, FRANCE, ASSIGNOR TO HIMSELF AND BERNARDO ANTOGNINI, OF NEW YORK, N. Y.

IMPROVEMENT IN INDIA-RUBBER HEELS OF BOOTS AND SHOES.

Specification forming part of Letters Patent No. 35,056, dated April 22, 1862.

To all whom it may concern:

Be it known that I, PIERRE BOISSET, of the city of Paris, in the Empire of France, have invented a new and useful Improvement in Boots and Shoes; and I do hereby declare that the following is a full and exact description of the same, reference being had to the accompanying drawings, and to the letters of reference marked thereon.

Figure I represents a section of a shoe. The remaining figures represent details referred to in the description.

Similar letters represent similar parts.

The nature of my invention consists in the application and combination, with an india-rubber heel, of metal points to prevent the wearing away of said heel.

In the accompanying drawings, A represents the sole of a boot having the heel a and shank b or instep made of india-rubber, with the forward part, d, of the sole made of leather and attached to the shank by any suitable means.

B represents part of the upper-leather or vamps, which is turned in between the outer and inner soles, and C represents the inner sole of the boot or shoe. To attach this inner sole, C, and the upper-leather B to the india-rubber shank and heel of the outer sole, A, I use screws s, provided with heads and screwed in from the inside or outside of the shoe, or I use screw-wire x, screwed in either from the outside or from the inside, or in some cases I use both these descriptions of screws combined. By the use of these screws for attaching india-rubber soles the upper-leather

B is compressed more tightly between the inner sole, C, and the outer india-rubber sole, A, than can be done by any other method of fastening india-rubber soles to boots or shoes and prevents the entering of any moisture into the same.

To prevent the wearing away of the india-rubber heel a, I incorporate into the same one or two frames, m, (see Fig. II,) with metal points o, attached in such a manner that the ends of said points o, which may be round, square, or any other shape, come flush with the bottom of the heel. This frame or frames may be arranged in such a manner that the metal points o will be only on that side of the heel most subject to wear, or go all around the heel, as may be desired.

In the after end of the heel a, I further incorporate a metal box or frame, D, provided with projecting ribs or pieces 2. This box receives the spur, and is prevented from coming loose by its ribs or projections 2.

The box D to receive the spur, as well as the frame or frames m, with metal points o, are incorporated into the india-rubber heel a during the process of making the same.

What I claim as my invention, and desire to secure by Letters Patent, is—

Making the heel-piece a of an india-rubber sole with a frame or frames, m, provided with points o, incorporated therein, in the manner and for the purpose substantially as set forth.

PIERRE BOISSET.
